APPARATUS FOR ROASTING MATERIAL

Application filed March 27, 1929. Serial No. 350,252.

My invention relates to apparatus for roasting material, and particularly to such apparatus having a furnace in which material comprising a metal compound may be 5 roasted to produce a metal oxide.

An object of my invention is the provision, in an apparatus of the character described, of means for controlling the temperature in the furnace to conserve heat and to control the 10 reaction in the furnace.

Another object of my invention is the provision, in an apparatus of the character described, of means effecting the discharge of substances given off from the material, at a 15 comparatively low temperature to prevent coalescing and sintering of the substances, which would otherwise occur at higher temperatures.

Another object of the invention is the provision of improved means for supplying air 20 to the furnace.

A still further object of the invention is the provision of improved means for passing material into the furnace and of improved 25 means for discharging material therefrom.

My invention possesses other objects and valuable features, some of which will be set forth in the following description of my invention which is illustrated in the drawings forming part of the specification. It is to be understood that I do not limit myself to the showing made by the said description and drawings, as I may adopt varying forms of 30 my invention within the scope of the claims.

Referring to the drawings:

Figure 1 is a more or less diagrammatic longitudinal sectional view of the apparatus, portions being shown in elevation to disclose 35 the construction clearly.

Figure 2 is a transverse sectional view taken in a plane indicated by line 2—2 of Figure 1.

Figure 3 is a transverse sectional view, partly in elevation, looking in the same direction

as Figure 2, and illustrating a modified form of feeding means which may be employed with the furnace.

In terms of broad inclusion, the apparatus comprises a furnace in which the material 50 is roasted; and preferably the furnace is provided adjacent one end with an expansion and cooling chamber for substances formed during combustion of material. Flues, opening from the furnace at different portions 55 thereof, are provided. Preferably one of the flues opens from the expansion chamber, while another of the flues opens from the opposite end of the furnace, dampers being positioned in the flues for controlling the flow 60 of substances from the furnace and the reaction therein. It is preferred to have the flues in communication, so that the vaporized substances may leave through a single exit. Means are provided for passing material into 65 the furnace, and means are also provided for discharging residue therefrom. Preferably the side of the furnace is provided with an air duct for permitting intermittent flow of 70 air into the furnace.

I have chosen, as a preferred embodiment of my invention, an apparatus which is used for the production of zinc oxide from materials such as zinc ore, zinc sulphide or zinc carbonate, although I am aware that the apparatus may be used for roasting many other metal compounds, such as those containing copper or cadmium. Also, the apparatus may be used for the roasting of non-metallic materials, such as for the production of sulphur 80 dioxide from sulphur or sulphur ores.

In greater detail, the apparatus comprises a roasting furnace, which is preferably cylindrical to form a drum 2, made of suitable material such as iron or steel. The drum is rotatably mounted by means of annular gears 3, surrounding the drum and fixed thereto by suitable means such as brackets 4; and the gears mesh with pairs of spaced pinions 6, journaled in suitable bearings beneath the 85 90

drum. A drive shaft 7, driven from any suitable prime mover, carries one of the pinions of each pair at the same side of the pairs; hence by rotating the drive shaft, rotation of the furnace is effected.

The furnace is provided at each end with apertures 8 surrounded by outwardly extending circular flanges 9, projecting into stationary hoods 11 and 12, which are held by suitable supports 13 and 14 respectively. Stationary hood 11 is at the discharge end of the furnace; and adjacent this end of the furnace and spaced inwardly therefrom is a circular apertured plate 16 forming an expansion chamber 17, which is preferably unlined. The remaining portion of the furnace provides a combustion chamber 18 which is preferably lined with any suitable refractory material 19, such as fire brick, and forming stepped sections which decrease in cross section toward the feeding end of the furnace, so that material fed therein may work toward the discharge end when the furnace is rotated. It is apparent, however, that a sloping furnace may be employed instead of the latter construction.

At the feeding end of the furnace at which hood 12 is located, and passing through the hood 12, are provided a burner 20, which may be either an oil or gas burner, and an air line 21 for supplying air to the furnace as desired. The aperture 8 adjacent this end of the furnace is partially closed by a semi-circular plate 22, fixed to the hood and having an aperture through which material from a screw conveyor 23 may be passed into the furnace. Any suitable means may be employed for driving the conveyor, although I prefer to drive it from drive shaft 7 by sprockets 24 and chain 26.

Means are provided for controlling the temperatures and reactions in the furnace. A flue 27 opening from the expansion chamber 17 of the furnace and into stationary hood 11, is provided with a damper 28; and a flue 29 opening from the opposite end of the furnace and into stationary hood 12, is provided with a damper 31. Preferably flue 27 is bent at right angles and communicates with flue 29, which in turn may be connected with an exhaust fan 32, from which the substances given off during combustion of material may be led to suitable bag houses for separation. A damper 33 is preferably placed in the discharge hood 11, also to provide a temperature control.

By the use of the described arrangement of flues and dampers, delicate control is provided, resulting in a fine product and conservation of heat. For example, if the apparatus is used for producing zinc oxide from zinc carbonate, the zinc carbonate is first finely divided and mixed with crushed coke, and the material is fed into the furnace as described. Combustion is initiated by the

burner 20, sufficient air being provided through air line 21. At a temperature of between 2200° F. and 2400° F., the following reactions occur, in which the coke aids in the combustion to form pure zinc vapor which oxidizes to zinc oxide:

75

If the temperature in the combustion chamber of the furnace is too low and therefore the reaction is incomplete, the dampers may be so adjusted as to hold the vapors in the furnace a longer period, such as by partially closing damper 28 and opening damper 31. If the temperature is too high, damper 28 may be opened further to provide more draft through the furnace. These conditions may be determined by a skilled operator who observes the character of the flame. Also, a temperature control is obtained by means of damper 33 in the discharge hood.

80

In the expansion chamber, the vapors expand and cool; and preferably the dampers 28 and 31 are regulated to maintain a temperature of between 400° and 500° F. of the substances that leave the expansion chamber and pass out through flue 27. In the furnaces heretofore used for roasting zinc ores, the gases leave at a temperature of about 1800° F., at which temperature the ZnO sinters and coalesces into large masses, which is undesirable for a quality product.

85

It is to be noted that since the temperature of gases leaving the furnace is very low, as compared with that of prior furnaces, a vast amount of heat is conserved; therefore it is unnecessary to have the burner 20 in continual operation, it being only necessary that it be burning when the temperature in the combustion chamber falls off.

100

Means are provided for intermittently discharging residue and ash from the furnace. Adjacent the expansion chamber 17, a conduit 34, lined exteriorly with refractory material, is positioned. Referring to Figure 2, the conduit is disposed angularly with respect to the radius of the furnace, so that when it is on the underside thereof it is disposed substantially perpendicular to a line 36 which indicates the relatively constant angle of repose of material in the drum, effected by rotation thereof in the direction of the direction arrow. Material will begin to discharge at this point. Upon movement of the conduit approximately 90°, it will then be substantially parallel with the surface of the material in the drum, hence any material remaining in the conduit will slide back onto the material in the drum and at the upper portion thereof, without creating dust particles that might be carried out of the drum with products of combustion. The speed of

105

110

115

120

125

130

rotation of the drum for a given material is practically always the same; and at a constant speed, the material will lie at a substantially constant angle of repose; hence 5 the inclination of the conduit may be readily ascertained.

When the conduit 34 is on the lower side of the drum, material will fall therethrough. When the conduit is on the upper side of the 10 drum, it is preferred to have it closed to conserve heat; therefore a cover 37 is hinged to the furnace adjacent the edge of the outer opening of the conduit, the cover being provided with a stop 38, adapted to limit outward movement thereof, so that when the cover is on the under side of the furnace, the conduit is open, and when it is raised upon rotation of the furnace, the cover may fall by gravity to close the conduit.

20 In addition to the discharge conduit 34, I preferably provide a large clean-out port 39 and cover 41 therefor, in order that the furnace may be cleaned when desired.

Air ducts are provided in the furnace, 25 which is formed with apertures 42 on opposite sides thereof. Conduits 43, communicating with these apertures, project into the furnace for supplying air thereto. These conduits are preferably lined with refractory material exteriorly thereof, and are provided with covers 44 hinged to the furnace in a manner the same as that described for cover 37 of the discharge conduit 34; so that during part of the furnace rotation, an aperture 35 is open to permit passage of air and during another part of the rotation, the cover automatically closes the aperture.

In Figure 3, I have illustrated a modified form of means for passing material into the 40 furnace, the rest of the apparatus construction being the same as that described. A conduit 46, projecting into the furnace, is disposed angularly with respect to the radius of the furnace and, when on the underside of 45 the furnace, substantially perpendicular to a line 47 indicating the constant angle of repose of material in the furnace when it is rotated. The conduit projects beyond the outer wall of the furnace; and at its outer end, it is provided with a scoop 48 having sides and a bottom but open at the top, and hingedly mounted on the conduit, the scoop being formed with stop 49 for limiting downward movement of the scoop when it is on 55 the underside of the furnace.

Upon rotation of the furnace, the scoop is adapted to gather material from a pile of material beneath the furnace; and upon raising of the scoop by rotation of the furnace, the material passes through the conduit and discharges into the furnace and onto the upper portion of material therein, without creation of dust particles as previously explained. When the scoop reaches an upper portion of its movement, it will fall by

gravity to close the conduit, the conduit being provided with a flange 51, adapted to form a closure for the open top of the scoop when it falls.

I claim:

1. An apparatus for roasting material comprising a furnace provided with an expansion chamber for substances formed during combustion of the material, a flue opening from the expansion chamber, a second flue opening from the furnace at another portion thereof, and dampers in said flues. 70

2. An apparatus for roasting material comprising a furnace provided with an expansion chamber for substances formed during combustion of the material, a flue opening from the expansion chamber, a second flue opening from the furnace at another portion thereof, one of said flues communicating with the other of said flues, and dampers in 80 said flues. 85

3. An apparatus for roasting material comprising a furnace having ends and provided with an expansion chamber adjacent one end thereof, means adjacent the other end 90 for passing material into the furnace, means for effecting movement of the material toward the expansion chamber, a flue opening from said expansion chamber, a second flue opening from the furnace adjacent the other end, and dampers in said flues.

4. An apparatus for roasting material comprising a furnace having ends and provided with an expansion chamber adjacent one end thereof, means adjacent the other end for passing material into the furnace, means for effecting movement of the material toward the expansion chamber, a flue opening from said expansion chamber, a second flue opening from the furnace adjacent the other end, one of said flues communicating with the other of said flues, and dampers in 100 said flues.

5. An apparatus for roasting material comprising a rotatably mounted cylindrical furnace having an aperture at each end thereof and provided with an expansion chamber adjacent one end thereof, hoods for said apertures, a flue opening from the furnace and into one of said hoods, a second flue opening from the furnace and into the other of said 110 hoods, and dampers in said flues. 115

6. An apparatus for roasting material comprising a rotatably mounted cylindrical furnace having an aperture at each end thereof and provided with an expansion chamber adjacent one end thereof, hoods for said apertures, a flue opening from the furnace and into one of said hoods, a second flue opening from the furnace and into the other of said hoods, dampers in said flues, and a damper 120 for the hood adjacent the expansion chamber. 125

7. An apparatus for roasting material comprising a rotatably mounted cylindrical furnace, means for rotating the furnace, and

a conduit leading into the furnace for the passage of material and mounted for rotation therewith, said conduit being angularly disposed with respect to the radius of the furnace.

8. An apparatus for roasting material comprising a rotatably mounted cylindrical furnace, means for rotating the furnace, a conduit leading into the furnace for the passage of material and mounted for rotation therewith, said conduit being angularly disposed with respect to the radius of the furnace, and a hinged cover for said conduit.

9. An apparatus for roasting material comprising a rotatably mounted cylindrical furnace having an aperture adjacent each end thereof, an expansion chamber and hood adjacent the aperture at one end thereof, a hood for the aperture adjacent the other end, a flue opening from the furnace and into one of said hoods, a second flue opening from the furnace and into the other of said hoods, and dampers in said flues.

In testimony whereof, I have hereunto set
25 my hand.

CHARLES J. SCHIFFERLE.
